UNITED STATES PATENT OFFICE

132,942

DESIGN FOR A COMBINED CHAIR, DESK, AND BACK REST

William J. Bargen, Waukegan, Ill.

Application May 5, 1941, Serial No. 100,793

Term of patent 14 years

To all whom it may concern:

Be it known that I, William J. Bargen, a citizen of the United States, residing at Waukegan, in the county of Lake and State of Illinois, have invented a new, original, and ornamental Design for a Combined Chair, Desk, and Back Rest, of which the following is a specification, reference being had to the accompanying drawing, forming a part thereof.

In the drawing:

bined chair, desk, and back rest embodying my new design.

Figure 2 is a front elevational view of the chair and back rest portion of the article; and

The dominant features of my design are shown in full lines in the drawing.

I claim:

The ornamental design for a combined chair, desk, and back rest, as shown and described.

WILLIAM J. BARGEN.
